UNITED STATES PATENT OFFICE

WINTHROP WITHTHINGTON, OF CLEVELAND, OHIO, ASSIGNOR TO AMERICAN FORK & HOE CO., OF CLEVELAND, OHIO, A CORPORATION OF OHIO

BROOM RAKE

Original No. 1,706,507, dated March 26, 1929, Serial No. 147,678, filed November 11, 1926. Application for reissue filed August 14, 1929. Serial No. 385,770.

My invention relates to broom rakes and relates particularly to broom rakes having metallic tines.

An object of my invention is to provide an improved form of broom rakes wherein like metallic strips are assembled together into a broom to provide a broom having the qualities of strength, flexibility and durability, to an exceptional degree.

10 Another object of my invention is to provide an improved form of broom rake which may be inexpensively manufactured and which will be durable and efficient in use.

15 Another object of my invention is to provide an improved form of broom rake in which hand operations in the making of the rake are largely avoided.

Another object of my invention is to provide an improved form of broom rake having 20 elongated tines, of light weight and in which the flexibility and resistance to flexure are very efficiently distributed along the length of the tines.

Other objects of my invention and the 25 invention itself will become apparent by reference to the following description of an embodiment of my invention and in which description reference will be had to the accompanying drawings illustrated the said embodiment.

Fig. 1 shows a broom rake embodying my invention in plan view.

Fig. 2 shows a vertical medial sectional view of the said embodiment.

35 Fig. 3 shows an enlarged sectional view taken on the line 3—3 of Fig. 1.

Figs. 4 and 5 show enlarged fragmentary sectional views taken on the lines 4—4 and 5—5, respectively, of Fig. 1.

40 Fig. 6 shows a plan view of a re-enforcing element employed on the foregoing embodiment in blank form.

Fig. 7 shows a plan view of a re-enforcing bar employed in the foregoing embodiment.

45 Fig. 8 shows a plan view of the embodiment of Fig. 1, enlarged to more clearly illustrate the twist in the tines, and Fig. 9 shows a transverse sectional view taken on the line 9—9 of Fig. 8.

50 Fig. 10 shows a plan view of a clamping

plate employed in the said embodiment of my invention.

Fig. 11 shows a side elevational view of a portion of the broom rake of the foregoing figures comprising the clamping mechanism therefor, in blank form; and Fig. 12 is a side elevated view after the same has been bent.

Referring now to the different figures of the drawings in all of which like parts are designated by like reference characters, at 1, 60 I, generally show a clamp comprising a substantially V-shaped metallic plate 2 having upwardly extending inturned flanges 3 adapted to retain a top plate 4 in contact with a plurality of metallic tines 5 clamped together 65 in a group in the clamp 1. Apertures 6 and 7 are provided in the plate 2 and grip plate 31 for the reception of bolts 8 and 9 to secure the clamp 1 and tines 5 on a handle 10, which bolts pass through apertures 11 and 12 provided in the handle for that purpose and are secured together by the nuts 13 and 14. An inwardly extending transverse detent 15 is preferably stamped in the plate 2 adapted to project into slots 16 cut in each of the tines 70 adjacent their handle ends to prevent their dislodgment from the clamp when the top plate has been secured in place by the inturned flanges 3. Before the tines are tempered and before they are placed within the 75 clamp 1 they are twisted at substantially 90 degrees upon themselves at 17 free of, but adjacent the clamp 1, to present their flat portions 18 extending away from the handle, and to provide for better clamping of the tines in 80 the clamp; they are also formed with bent ends 20 to form fingers 21 before being tempered.

The tines are preferably formed from spring sheet steel, of a hardness and temper 90 so that they will not be brittle and easily subject to breakage, but at the same time, so hard that the tines will be quite resilient, and when deflected and the deflecting pressure being removed will be restored to normal un-deflected form. The dimensions of the tines will depend upon the nature of usage to which the rake will be subjected.

By virtue of the inclined flanges 3 and the twist in the tines they extend from the clamp 100

in a fan like formation and preferably present an arcuate end configuration for contact with the surface to be raked.

Intermediate the ends of the tines I provide a reinforcement 25 disposed at such a point that it will effectually retain the tines assembled and to re-enforce the tines, and at the same time being so disposed so that it will effect a proper resiliency in the finger ends of the tines. The said re-enforcement preferably comprises an arcuate shaped strip of steel 26 having a plurality of laterally projecting fingers or flanges 27 projecting from each side of the strip 26, at predetermined spaced intervals from end to end. The fingers or flanges are so spaced apart as to provide for a tine to be disposed between two of them when applied to the tines. This strip is best shown in blank form in Fig. 5 of the drawings. The ends of the strip 26 are rounded at 28 to provide fingers or flanges 29 to be bent around the most laterally disposed tines to clamp them. At 30 I show a strip of sheet steel adapted for co-operation with the strip 26 and of arcuate formation having the same degree of curvature as the strip 26.

The re-enforcement just described is applied to the tines after they have been placed in the clamp 1 by initially bending the fingers or flanges 27 and 29 into an upright position and inserting the strip from the underside of the tines so that the fingers or flanges extend above the tines, and the fingers or flanges 29 extend beyond the outermost tines.

35 The strip 30 is then placed on the tines on the opposite side from the strip 26 and between the upstanding flanges or fingers. The strip 30 is shorter than the strip 26 and the ends thereof are disposed between the flanges or fingers 29. The rake is now placed in a power press and the fingers or flanges 27 and 29 are simultaneously bent inwardly and securely grip the strips 26 and 30 and the tines 5 together insuring a rigid re-enforcement for the tines.

40 The rake is adapted to be employed on lawns, gardens, gravel walks, and the like, and may be operated with a sweeping motion like that effected by a person operating an ordinary broom, permitting the person to stand erect, the raking being rendered less fatiguing.

45 The broom rake constructed as described with tines bound together by the intermediate disposed re-enforcing strips and twisted intermediate the re-enforcement and handle possesses a very desirable distribution of resiliency, the twisted tine portions resisting deflection more than untwisted tines could do, and the re-enforcement accomplishing a similar result to the stitching of ordinary brooms, in the distribution of resiliency and resistance to bending when the broom is used.

50 At the same time the twisted tines at the handle end are capable of being bundled to-

gether in a small compass, flat sides towards each other and contacting at the tine ends. Also the twisting of the tines together with the notching of the same permits the effective use of a detent such as that shown at 15, projecting into the notches to prevent longitudinal displacement of the tines.

55 The clamp for the tines, employed for the purpose of securing the tines to the handle, is constructed, as shown, to have a housing 2 with a cover 4, the cover plate 4 being held tightly against a side edge of each of the tines by virtue of the inturned flanges 3 in the form of ears, which enter border notches 41, 42, 43 and 44 in the plate at its corners, the ears being then bent over the outside surface of the plate, as illustrated, to securely clamp the plate against the tines. Fig. 10 shows the form of the clamping plate with the border notches for the reception of the housing clamping ears, the plate being perforated to receive a bolt 9 which is projected between a pair of intermediately disposed tines and aligned perforations through the handle at 12 and the reinforcing plate 31. The handle end is flattened on one side, being cut away as shown at 45, to form a flat seat 46 for the clamp housing 2, and which provision prevents rotational displacement of the clamp on the handle. As illustrated, I provide one of the clamping elements, comprising the plate and housing, with a transverse rib 15 which is adapted to project inwardly towards the other element, in the embodiment illustrated, the plate, and as a 100 detent to enter notches 16 provided at a side edge of each of the tines 5. The disposition of the rib 15 in the tine notches effectually prevents displacement of the tines longitudinally and permits the secured ends of the tines 105 to be disposed in a clamping housing 2, as shown, in a neat and compact manner, this being possible because of the right-angled twist given each of the tines prior to insertion of their ends in the clamping housing.

110 In assembling the clamping mechanism, the converging tine ends are placed within the housing 2 with their notched sides receiving the inwardly projecting rib 15 of the housing, the flanges 3 at such time being upright and projecting in alignment with the housing sides 47 and 48. The plate 4 is then placed over the outer edges of the tines, as illustrated in Fig. 3, and the flanges 3 are bent over, as shown, to retain the plate 4 in its clamping position. The metallic material, such as mild steel, of which the clamping elements are made, is possessed of sufficient strength and plasticity as to permit the bending over of the flanges and to cause these 120 flanges to retain their formed position after being bent. The bolts 8 and 9 are then inserted in their securing positions, as illustrated.

125 Having thus described my invention in a

specific embodiment, I am aware that numerous and extensive departures may be made from the embodiment herein illustrated and described, but without departing from the spirit of my invention.

5 I claim:

1. In a broom rake, the combination with a plurality of elongated metallic strips forming rake tines, each of the strips divergently extending from the handle and bundled together at their handle ends with their flat sides brought together, each of the tines being notched adjacent its handle end, all of the notches being in substantial alignment when the tines are bunched, and a clamp for the bunched tine ends embracing the same and comprising a metallic enclosure with an inwardly extending rib projected within the tine notches, and securing means to secure the clamp to the handle.
- 10 2. In a broom rake, the combination with a handle of a plurality of elongated metallic strips forming rake tines divergently extending from the handle and bundled together at their converged ends with the adjacent flat sides of adjacent tines disposed in opposition, each of the tines being notched, a clamp carried by the handle embracing the bunched tine ends comprising a metallic enclosure, and key means for the enclosure projected within the tine notches to prevent longitudinal movement of the tines within the clamp.
- 15 3. In a broom rake, the combination with a handle of a plurality of elongated metallic strips forming rake tines divergently extending from the handle and bundled together at their converged ends with the adjacent flat sides of adjacent tines disposed in opposition, each of the tines being notched, a clamp carried by the handle embracing the bunched tine ends comprising a metallic enclosure, and key means for the enclosure projected within the tine notches to prevent longitudinal movement of the tines within the clamp, said clamp comprising a box having a side, said key means being integrally projected from said side.
- 20 4. In a broom rake, the combination with a handle of a plurality of elongated metallic strips forming rake tines, each having a half twist intermediate its ends, divergently extending from the handle and bundled together at their converged ends with the adjacent flat sides of adjacent tines disposed in opposition, a clamp carried by the handle embracing the bunched tine ends, and said bunched tine ends and clamp being interlocked to prevent longitudinal movement of the tines within the clamp.
- 25 5. In witness whereof I hereunto affix my signature this 17th day of July, 1929.

WINTHROP WITHINGTON.
